HAND-HELD LITTER-COLLECTING DEVICE

John H. Coul, 1 Leland Road, Natick, Mass. 01760

Filed Nov. 24, 1969, Ser. No. 20,240

Term of patent 14 years

Int. Cl. D15—07

U.S. Cl. D49—13

FIG. 1

FIG. 2

FIG. 3

FIG. 4

FIG. 5

FIG. 6

FIG. 7

FIG. 1 is a perspective view of a litter-collecting device incorporating my novel design;

FIG. 2 is a left side elevational view of the device;

FIG. 3 is a right side elevational view thereof;

FIG. 4 is a top plan view thereof;

FIG. 5 is a bottom plan view thereof;

FIG. 6 is a front end elevational view thereof; and

FIG. 7 is a rear end elevational view thereof.

I claim:

The ornamental design for a hand-held litter-collecting device, substantially as shown.
